UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

METHOD OF KNITTING FINE-GAGE FABRICS.

1,248,019.

Specification of Letters Patent.

Patented Nov. 27, 1917.

Application filed May 15, 1915. Serial No. 28,440.

To all whom it may concern:

Be it known that I, ROBERT W. SCOTT, a citizen of the United States, and resident of Boston, in the county of Suffolk and State 5 of Massachusetts, have invented certain new and useful Improvements in Methods of Knitting Fine-Gage Fabrics, of which the following is a specification.

My invention relates to an improved art 10 or method of knitting fabrics, including fine-gage or closely-spaced fabrics, on a series of instruments. While my invention may be carried out upon any series of hooked instruments, it is especially adapted to be 15 practised in connection with any of certain familiar types of knitting machines, such as straight or circular machines employing movable hooked needles.

One object of my invention is to so order 20 the steps taken in manipulation of a yarn or yarns by or upon such a series of instruments as to produce fabrics characterized by a greater variation in width between their widest and their narrowest portions, 25 the number of knit wales remaining constant, than heretofore has been possible. Another object is to decrease the size of the loop knit by instruments such as knitting machine needles relatively to the size and 30 spacing of the instruments. Another object is to provide for the making upon a single series of instruments of seamless hosiery which shall be shaped or fashioned by variation in the length of stitch through a range 35 or to a degree heretofore impracticable by the use of said instruments.

In the accompanying drawings,

Figure 1 is a diagram showing fabric in the course of formation in the new manner 40 with the aid of knocking-over instruments, such as web-holders, and latch needles;

Fig. 2 is a similar diagram showing the old mode of forming the fabric;

Fig. 3 is a diagram illustrating on a large 45 scale certain movements of and tensional stresses given the yarn at the time of formation of the new loop;

Fig. 4 is a comparative diagram illustrating needles;

Fig. 5 is an illustration of the seamless fine gage stocking of the prior art, and

Fig. 6 is an illustration of a stocking produced by my new method.

I will now explain my new method with 55 reference to the instruments shown in Fig.

1 as one example only of implements suitable to aid in performing the steps of said method. The instruments *n* may be hooked needles and the instruments *w* may be fixed or movable web-holders or other knocking-over devices having upper edges in a plane 60 *P*. The size and distance apart, or gage, of needles *n* may be determined by a grooved carrier or holder in which they are movable.

My new method will best be understood 65 by comparison with the old procedure. Referring now to Fig. 2, which shows a series of old instruments comprising hooked needles *n'* and web-holders *w*, working in the old way, previous courses having been knit 70 on such instruments as at 1 and 2, the new course 3 is formed of yarn *y* by drawing in turn a new loop through each loop of the course 2 detained at the web holders *w* against movement with needles drawing 75 loops; for instance, as a machine operation, by causing relative motion between the needle carrier, needles and web-holders on one part, and the needle cams and yarn guide 80 on the other part, the needles being carried downward to draw their loops at slope *S* when acted upon by a stitch cam (not shown), until their tips are beneath plane *P* a distance or draft fixing the amount of 85 new yarn taken at each needle in course 3.

When the instruments are operated in the usual manner just described, I have observed that with the minimum draft, the finest needles and with the remaining conditions of the prior art as known to me at 90 their best, that the narrowest or shortest-loop fabric which can be knit still has needle wales larger than the sinker wales joining them, each course containing more yarn than is necessary. I have determined the 95 cause of the relatively wide fabric and large needle loops to be the freedom of the loops of a previous course such as the course 2 to be displaced downwardly by a needle as at 6 in the act of drawing a new-course loop. 100 The loop *z* of a previous course 2 merely resting upon the web holders *w* is carried downward by the stitching needle through a distance measured at least by the full length of a loop of said course 2, and a needle drawing a new loop *a* is required to be drawn a further distance still beneath plane *P* to cause its new loop *a* to penetrate the old loop *z*.

Referring now to Fig. 1 my new method 110

comprises manipulating the loops of a previous course with respect to a needle about to draw a new loop in such a manner as to avoid drawing the new loop to an excessive length beyond that necessary to take it through the old loop. I accomplish this by placing the previous-course loop about to be penetrated by a new loop under stress tending to move it in a direction opposite to the motion of the needle penetrating it, and by simultaneously placing the said loop of the previous course under lateral tension to draw it up tightly on to the neck of the new loop. Such a manipulation of the old or previous-course loop, by whatever means it may be caused, results in the penetration thereof and completion of the new loop at a point relatively near the knocking-over plane P as compared with the operation of the needles of the prior art, and for this reason the amount of yarn taken into the new loop (the amount measured by the recession of the hooked needles beneath the plane P and instruments w) is materially lessened.

My invention is not limited to any particular means for applying upward stress and tension to the previous-course loop, but I have also devised and will now explain one effective means for producing the said stress and the said tension. For this purpose I utilize the obstacle to the free movement of a yarn loop always present in latch needles, and constituted by the exterior face of the needle cheeks and the closed latch and the point of the hook. Whatever the form of such needles, there is some part of them at which the loop tends to hang, and on which the loop in which a needle is moving is detained and carried along with the needle. This point may be, and usually is, the spoon or enlargement at the tip of the latch. I therefore provide needles, as shown at n, Figs. 1 and 4 with hooks h and latches d meeting at a point separated from the tip of the needle by a distance sufficient to bring the obstacle to free passage of the loops materially beneath the tip. The said distance depends somewhat upon the form of the needle-wave and the gage of the needles, but in any instance I place the obstacle at one needle following another down the retarding slope S of the wave of movement so that its end will be materially beneath the tip of the preceding needle. By preference, the obstacle on each needle culminating at latch spoon d', ends at a point substantially as much beneath the tip of a preceding needle as the tip of said preceding needle is beneath the tip of the following needle.

Operation of the instruments under the same conditions as before now proceeds in a new order to produce the result indicated in Fig. 1, in which the needle at VI has

drawn barely enough yarn y for new course 3 beneath plane P determined by the instruments w. Before this time (see needle VII) needle VI will have passed the end of its obstacle at d' through the loop x² of previous course 2, and the following needle VII will still engage and continue to drag downwardly its loop x by engagement with its latch d, as shown. Yarn for the enlargement and displacement of loop x is taken 75 from the preceding loop x² now free upon its needle VI.

Owing to the relatively fixed abutment w, loop x² is moved upwardly in the direction of the arrow f and tension is placed upon it to make it smaller by draft on its yarn acting about the instrument w in the direction of arrow g. Little or no yarn can be given up to loop x from the loop x² on a following needle VIII, by reason of the 85 entrance into it of the slope of latch d leading to spoon d' of said following needle, and the whole motion and tension on the neighboring previous-course loops due to the enlargement and displacement of the loop 90 on the needle following the stitching needle is made available to lift and tension the loop being penetrated by the new stitch c of new course 3. The old or previous course loop is thereby independently moved in opposition to the needle to a point near the plane P.

The draft to be given the needles may now be reduced to a point at which the loop c is long enough, and only long enough, 100 when extended by robbing its neighbors, to pass around the widest part of the needle, the tip of a needle at the lowest position being materially nearer the plane P than has heretofore been possible.

It will now be apparent that with respect to a series of needles of a given gage my new method provides for decreasing the least width of the fabric without in any way limiting capacity to increase the width 110 by increasing the draft of the needles. Practice of my method is for this reason of peculiar advantage in the production of fashioned hosiery, and particularly of fashioned seamless hosiery produced upon knitting machines having needles arranged in a closed figure such as a circle, or in two adjacent flat beds. All such seamless stockings, when approaching in fineness of gage 115 the well-known fine stockings made by flat-fashioning and seaming, with the aid of fixed spring needles and by an expensive series of operations including yarn-sinking and loop-transferring, have heretofore been defective by reason of too-wide heels, toes 120 and feet, as illustrated in Fig. 5, which shows such a seamless stocking after finishing. Said stocking, in order to have enough width at its wide parts without too loose and sleazy a texture, necessarily is made 130

upon so many needles that the phenomena pointed out above prevent a proper narrowing by shortening the stitches to make well-shaped ankles, heels, toes and feet. Such 5 stockings, made as narrow as possible at said parts, are finished by stretching and shrinking on a shaped board, but this operation can not be applied to decrease the length in direction L of the heel and toe or 10 L' for the heel, it being necessary to stretch the foot originally knit too short for that purpose (and heel and toe therewith) in direction L to shrink the foot in width; and to stretch the ankle and heel in direction L' 15 to shrink the ankle. Both heel and toe being already too wide, the heel and toe pockets in the finished stocking are so much over size as to prevent sale in competition with flat-fashioned stockings of the same 20 quality.

My new method enables a stocking having the same number of needle-wales throughout to be knit at the narrowest parts of courses so short as to avoid stretching except 25 for smoothing the fabric, and with heel and toe fabrics partaking of the same quality. For comparison, Figs. 5 and 6 have been supplied with dimensions in 30 inches taken respectively from a finished stocking of the prior art and from an unfinished stocking produced by my said method, both having throughout the same number of needle wales knit of the same 35 yarn, and exactly similar legs and tops (not shown).

What I claim is:

1. The art of knitting on a series of hooked needles comprising forming a previous course of loops and thereafter placing each of said loops successively under stress to move it off its needle during formation of a loop for a new course at said needle. 40
2. The art of knitting on a series of hooked needles comprising forming a previous course of loops and thereafter placing each of said loops successively under stress to move it off its needle and under lateral 45

tension during formation of a loop for a new course at said needle.

3. The method of knitting on a series of 50 needles comprising drawing a loop for a new course at a certain needle, and simultaneously acting upon a loop of a previous course at a neighboring needle only to move another loop of said previous course on said 55 certain needle over said new loop.

4. The method of forming on a series of knitting needles a course of short loops comprising first forming a previous course loop on each of said needles, and then in 60 succession moving said loops with respect to each needle over a new loop formed thereat, during maintenance of tension on said previous loop.

5. The method of knitting on a series of 65 needles, fabrics characterized by abnormally short courses comprising acting upon a previous course loop at each needle in turn to displace said loop at said needle, whereby to knock over and laterally tension another 70 loop of said previous course, and thereafter forming a new loop of yarn at said needle.

6. The method of knitting fabrics having short loops on a series of needles and a series of knocking-over members such as 75 web-holders defining a yarn detaining surface, comprising pulling upon the yarn of a previous course to move a loop of said course toward said surface at the time of pulling a new loop through said previous 80 course loop.

7. The method of knitting seamless stockings comprising first forming a tubular leg portion in any known or usual manner, and thereafter knitting tubular ankle, heel, foot 85 and toe portions of fabric narrowed by decreasing the length of stitch, said narrowing operation including moving and tensioning each loop of a previous course at the time of drawing a new loop through it, substantially as described. 90

In testimony whereof, I have signed my name to this specification.

ROBERT W. SCOTT.
